UNITED STATES PATENT OFFICE.

STEFANO CHIABELLO, OF BROOKLYN, NEW YORK.

CAR STAKE.

Application filed August 12, 1927. Serial No. 212,577.

This invention relates to improvements in car stakes and more particularly to telescopic car stakes for flat and gondola railway cars.

5 The primary object of the invention is to provide a telescopic car stake which is extremely simple and durable in construction as well as efficient in use.

Another object is to provide an improved 10 telescopic car stake embodying simple and efficient means for releasably maintaining the same in extended condition.

15 A further object is to provide an improved telescopic car stake of the above kind having simple and efficient means whereby the load binding chains may be readily adjusted to the height of the load.

20 Other objects will become apparent as the nature of the invention is better understood, and the same consists in the novel form, combination and arrangement of parts hereinafter more fully described, shown in the accompanying drawings and claimed.

25 In the drawings, wherein like reference characters indicate corresponding parts throughout the several views,

Figure 1 is a fragmentary longitudinal section of a gondola car equipped with a 30 telescopic stake constructed in accordance with the present invention, the stake being in extended condition and shown in side elevation as seen looking toward the inner sides thereof;

Figure 2 is a fragmentary transverse section taken upon line 2—2 of Figure 1;

Figure 3 is a vertical section taken upon line 3—3 of Figure 2;

Figure 4 is a view similar to Figure 3 with the stake in collapsed condition; and

40 Figure 5 is an enlarged horizontal section taken upon line 5—5 of Figure 1.

Referring more in detail to the drawings, the present car stake includes telescopically associated lower and upper sections 5 and 45 6, preferably in the nature of open-ended rigid metallic tubes of rectangular cross-section as shown in Figure 5, whereby relative turning of the sections will be prevented.

The upper section 6 slidably fits into the 50 lower section 5 and has pairs of opposed horizontal sliding catch bolts 7 mounted in the lower end portion thereof. As shown, the pairs of catch bolts are mounted in spaced superimposed relation, and the inner 55 ends of the bolts of each pair are operatively connected by toggle links 8, the adjacent

pivotedly connected ends of which are pivoted to a vertical operating rod 9 that projects upwardly in the upper stake section 6 and terminates near the upper end of the 60 latter in a handle 10. Each pair of latch bolts is slidably mounted in a casing 11 suitably fixed within the stake section 6 and enclosing helical tension springs 12 which act to normally project the latch bolts 65 through the opposite side of the stake section 6. As shown, the inner ends of the latch bolts are provided with oppositely projecting lateral extensions 13 to which the inner ends of the springs 12 are attached, 70 the outer ends of the springs 12 being suitably attached to the outer ends of the casing 11. In view of the above construction it will be seen that by pulling upwardly upon the rod 9, the toggle links 8 will be broken 75 in an upward direction so as to effect the retraction or release of both pairs of locking bolts, while upon releasing the rod 9, the springs 12 will act to straighten the toggle links, lower rod 9 and project bolts 7. 80

Provided in opposite sides of the lower stake section 5 are pairs of spaced superimposed openings 14 outwardly into which the latch bolts 7 are adapted to be projected when the upper stake section 6 is elevated 85 to extended or operative position. When the bolts 7 are thus projected into the openings 14, it will be evident that the upper stake section is effectively maintained in its elevated operative position. By employing 90 two pairs of opposed locking bolts in spaced superimposed relation, a most effective latching engagement with the lower section is had and the upper section is effectively braced against lateral strains and accidental 95 release. Any suitable means may be provided for fastening the stake to the car and for preventing movement of the section 6 entirely out of section 5, but as this forms no specific part of the present invention disclosure thereof is refrained from herein. Obviously, the stake may be applied to the outer side of the sill of a flat bottom car, but as shown, the same is mounted at the inner side of the side wall 14 of a gondola 100 car.

In order to exclude the entrance of dirt and other foreign matter into the stake section to an objectionable degree, the upper end of the upper stake section 6 is preferably closed by means of a hinged cover or cap 15 adapted to be readily opened to fa- 105

cilitate access to the handle 10 of the latch operating rod 9.

Provided in the inner side wall of the upper stake section 6 and extending substantially from end to end of the latter is a longitudinal elongated slot 16 in which is slidably fitted an H-shaped slide block 17 to which is attached one end of a load binding chain 18. This load binding chain is adapted to be extended to the slide block 17 of another similar stake mounted upon the opposite side of the car directly opposite the present stake shown, as is generally well known in the art. As the slide blocks are freely slidable in a vertical direction, it is evident that the load binding chains 18 may be readily adjusted vertically to the height of the load relative to the upper stake section.

In use, assuming that the stake is collapsed as shown in Figure 4, the cover 15 is open and by inserting the fingers into the upper end of the stake section 6, the handle 10 may be grasped. By pulling upwardly upon the rod 9, the latch bolts 7 may be positively fully retracted so as to offer no frictional resistance whatever to the elevation of the stake section 6. As soon as the stake section 6 reaches its upward limit of movement to operative position, the bolts 7 will be projected by springs 12 into the openings 14, thus effectively sustaining the section 6 in elevated position. The cover 15 is then closed and slide 17 is adjusted to the desired elevation in slots 16. When it is desired to collapse the stake, the cover 15 is again opened and the rod 9 pulled upwardly so as to release the catch bolts 7, and while exerting an upward pull upon the rod 9, the stake section 6 is forced downwardly into the lower stake section 5 to the position of Figure 4. As the stake section 6 is slightly longer than the stake section 5, the cover 15 will not interfere with lowering of said stake section 6, and by making the latter slightly longer, the necessity for removal of slide block 17 may be avoided.

From the foregoing description it is believed that the construction and operation as well as the advantages of the present invention will be readily understood and appreciated by those skilled in the art.

Minor changes may be made without departing from the spirit and scope of the invention as claimed.

55 What I claim as new is:—

1. A telescopic car stake comprising hollow lower and upper sections slidably fitted one within the other, opposed horizontal

sliding latch bolts mounted in the lower portion of the upper section and engageable with the lower stake section to hold the upper section in extended position, and a vertical pull rod within the upper stake section operable for releasing said latch bolts. 60

2. A telescopic car stake comprising hollow lower and upper sections slidably fitted one within the other, opposed horizontal sliding latch bolts mounted in the lower portion of the upper section and engageable with the lower stake section to hold the upper section in extended position, a vertical pull rod within the upper stake section operable for releasing said latch bolts, said pull rod terminating in the upper end of the upper stake section, and a cover for the upper end of the upper stake section, movable to uncover the latter and permit access to the pull rod. 65

70 3. A telescopic car stake comprising hollow lower and upper sections slidably fitted one within the other, opposed horizontal sliding latch bolts mounted in the lower portion of the upper section and engageable with the lower stake section to hold the upper section in extended position, a vertical pull rod within the upper stake section operable for releasing said latch bolts, and toggle link connections between the inner ends of the latch bolts and said pull rod. 75

80 4. A telescopic car stake comprising hollow lower and upper sections slidably fitted one within the other, means to releasably hold the upper section in extended position, said upper section having an elongated vertical slot in the inner side thereof extending substantially from top to bottom of the same, an H-shaped slide block slidably engaging the wall of said upper section at opposite sides of said slot and movable in the latter for vertical adjustment, and a load binding chain attached to said slide block. 85

90 5. A telescopic car stake embodying hollow lower and upper sections slidably fitted one within the other, spaced superposed pairs of opposed spring-projected latch bolts mounted for horizontal sliding movement in the lower part of said upper section, a vertical operating rod in said upper section terminating near the top of the latter, and toggle links connecting the inner ends of said latch bolts to said operating rod, the lower section having openings in the upper portion thereof to receive said bolts for holding the upper section in extended position. 105

110 In testimony whreeof I affix my signature.
STEFANO CHIARELLO.
